[57] CLAIM

The ornamental design for a combined portable holder for artist's material and display cover therefor, as shown and described.

DESCRIPTION

FIG. 1 is a top, left front perspective view of a combined portable holder for artist's material and display cover therefor;

FIG. 2 is a side elevational view, the opposite side being a mirror image thereof;

FIG. 3 is a front elevational view, the rear view being a mirror image thereof;

FIG. 4 is a bottom plan view; and,

FIG. 5 is a top, left front perspective view thereof in an exploded condition.
